Primary Examiner — Robert M Spear*Assistant Examiner* — Marissa J Cash(74) *Attorney, Agent, or Firm* — Robert W J Usher(57) **CLAIM**

The ornamental design for a power unit attachable to a folded paper airplane, as shown and described.

DESCRIPTION

FIG. 1 is an isometric view from the front, above and one side of a power unit attachable to a folded paper airplane showing my new design, (opposite side is identical);

FIG. 2 is an isometric view from the rear, above and opposite side;

FIG. 3 is a side elevation corresponding to FIG. 1;

FIG. 4 is a side elevation corresponding to FIG. 2;

FIG. 5 is a top view;

FIG. 6 is an isometric view from the front, below and the one side;

FIG. 7 is a bottom view;

FIG. 8 is a rear view; and,

FIG. 9 is a front view.
